UNITED STATES PATENT OFFICE.

CHARLES H. TRUAX, OF CHICAGO, ILLINOIS.

DESIGN FOR A DRESSING-STAND.

SPECIFICATION forming part of Design No. 26,930, dated April 20, 1897.

Application filed March 5, 1897. Serial No. 626,137. Term of patent 3½ years.

To all whom it may concern:-

Be it known that I, CHARLES H. TRUAX, a citizen of the United States, residing at Chicago, Cook county, State of Illinois, have invented a certain new and useful Design for Antiseptic Dressing-Stands, of which the following is a specification.

In the accompanying drawing I have shown a perspective view of my new design.

The leading features of my design consist of the upright standards, the horizontal shelves, the central inclosed space, and the front rectangular frames having curved portions extending into the space.

Referring to the drawing for a more particular description, A A are two vertical uprights, and A' A' are also two vertical uprights having curved portions a.

B B' B² B³ B⁴ are horizontal shelves extending between the vertical uprights.

C is a central inclosed space between the shelves B² B³, the front and side walls being

transparent. Extending between the shelves B² and B³ is a series of rectangular frames D, having cross-pieces d and bent projections d'. ²⁵ Extending into the inclosed space from the upper portions of these rectangular frames D are the curved portions D', one of the rectangular frames being shown extended forward, better illustrating the configuration of the ³⁰ curved portions D'.

The whole forms an æsthetic appearance, having a graceful contour, and producing a pleasing effect upon the eye.

What I claim is—

The design for antiseptic dressing-stands substantially as shown and described.

In testimony whereof I have signed my name to this specification in the presence of two subscribing witnesses.

CHARLES H. TRUAX. ³⁵
